SHOE MACHINES

Robert William Bradshaw, Leicester, England, assignor to United Shoe Machinery Corporation, Boston, Mass., a corporation of New Jersey

Filed Mar. 9, 1960, Ser. No. 13,849

Claims priority, application Great Britain Apr. 14, 1959
9 Claims. (Cl. 112—46)

This invention relates to machines for operating upon stitchdown shoes, in which a welt is sewn or otherwise attached to a work piece consisting of a projecting marginal portion of an outsole and the outturned flange of an upper by a seam extending entirely around the periphery of a shoe while the shoe is supported on a last in a sole uppermost or inverted position. More particularly, the invention resides in an improvement in a machine, such as that disclosed in United States Letters Patent No. 2,900,932, granted August 25, 1959, upon application of George Pickford and Ralph Ward.

In the machine of the prior patent there is provided mechanism acting automatically to sever a welt while being sewn to the projecting marginal portions of a stitchdown shoe through the engagement of the leading end of a welt already attached thereto with a feeler finger adapted to be pressed in a substantially horizontal direction against the bulging last supported portion of the shoe upper into a position to be actuated by the welt as the shoe is fed past it. It is well recognized that one of the difficulties encountered with the use of such machines is, that because the shoe is presented to the machine with the sole uppermost the end of the welt first attached to the shoe is hidden from an operator's line of vision by the projecting marginal portions of the shoe. Accordingly, it is impossible for the operator of the machine to determine if the welt engages the feeler properly, especially when it is realized that the trailing end of the welt to be attached to the shoe must be severed from the welt remaining in the machine in advance of the point of sewing operations without interrupting or delaying these operations. Unless it is possible to observe the action of the feeler clearly, it is difficult to favor its proper actuation by changing the manner of presentation of the shoe to the machine, so that there is a likelihood of producing an imperfection in severing the welt. If the welt is not severed at the correct position, the two ends overlap or a gap exists between them in a manner to prevent the best results from being obtained.

One of the several objects of the present invention is to provide an improved machine for attaching a welt or other strip of material about the marginal portions of a work piece, and especially for sewing a welt to a stitchdown type of shoe, in which machine the objections above referred to are avoided.

The illustrated embodiment of the invention comprises a shoe sole sewing machine having the usual stitch forming and feeding devices including a work support engaging the under side of the work piece operated upon, a presser foot engaging the upper side of the work piece where the visibility is unobstructed, a needle acting from above the work piece, a guide located below the level of the work piece for directing a welt along the work support to a position which is obscured by the projecting marginal portions of the work piece, and an electromagnetically actuated welt severing knife spaced in advance of the point of needle operation and having connected with it a control switch, in which means for actuating the control switch is mounted entirely above the level of the surface of the work piece at a position where unobscured visibility is possible. The control switch actuating means, in accordance with the invention, is arranged to be engaged by a length of thread extending from the first stitch

2

of a seam inserted by the needle as that thread length moves toward the sewing point a second time, the first stitch of the seam being inserted in a predetermined spaced relation from the leading end of the welt. In this way a more effective control is afforded for actuation of the welt severing knife than in the prior machine, and it is readily possible for an operator of the present machine to vary the position along the welt where the knife is actuated in accordance with the requirements dictated by the character of the work without the exercise of more than average skill and attention. As hereinafter illustrated, the means for actuating the control switch consists of a spring blade extending downwardly and disposed at a position clearly visible to the operator in close proximity to the uppermost surface of a work piece, such as a shoe sole, where the spring blade may be engaged by the length of thread extending from the first stitch. The length of thread which actuates the control switch is held taut manually in a position extending at an acute angle to the upper surface of the work piece.

Preferably, the engagement of the taut thread length with the switch actuating blade is assured by the use of a guiding member which acts to direct the thread length against the blade substantially in advance of its approach to the blade.

These and other features of the invention, as hereinafter described and claimed, will readily be apparent to those skilled in the art from the following detailed specification and claims, taken in connection with the accompanying drawings, in which:

FIG. 1 is a view partly in front elevation and partly in diagrammatic form of portions surrounding the sewing point of a lockstitch shoe sole sewing machine illustrating the features of the present invention;

FIG. 2 is a partially sectional view in right side elevation of a welt severing knife and its actuating mechanism in the machine of FIG. 1, looking in the direction of the arrow II;

FIG. 3 is a sectional plan view of parts of the machine of FIG. 1, illustrating a portion of a shoe during its presentation to the machine; and

FIG. 4 is a detail sectional view on a somewhat enlarged scale and looking from the left, of the parts surrounding the sewing point in the machine and of a shoe being operated upon.

The machine embodying the present invention is a lockstitch shoe sole sewing machine of the type disclosed in United States Letters Patent No. 2,056,670, granted October 6, 1936, upon application of Gouldbourn et al. The machine is a wax thread curved hook needle machine of the clamp feed type, although the invention would be equally capable of use in other machines, such as that of United States Letters Patent No. 2,271,611, granted February 3, 1942, upon application of Ashworth et al., or that of United States Letters Patent No. 1,169,909, granted February 1, 1916, upon application of Fred Ashworth, in which a work penetrating awl acts to feed the work.

The machine of the invention is equipped with a guide through which a welt or narrow strip enters in advance of the sewing point and is directed to the sewing point for application to the outflanged portion of an upper in a stitchdown shoe supported on a last. The machine is intended to insert a seam connecting together the welt, the outflanged upper and an outsole entirely around the projecting marginal portions of the shoe, and to return to the starting point, preferably with overlapping stitches, in order to insure firm attachment of the trailing end of the welt in engagement with the leading end first attached to the shoe. For the best quality of workmanship the ends of the welt are brought accurately into abutting relationship and a continuous seam is inserted across the abutting ends. In this way a reliable incon-

spicuous joint is formed between the ends of the welt. Heretofore, it has been possible to insert a continuous seam across accurately butted ends of the welt by means of a machine disclosed in the Pickford et al. patent, in which there is utilized, in addition to an electromagnetically actuated welt severing knife, a feeler finger adapted to be pressed in a substantially horizontal direction against the bulging last supported portion of the shoe upper into a position to be actuated by the leading end of the welt. Since both the feeler finger and the leading end of the welt are entirely obscured by the outflanged marginal portions of the shoe during the sewing operation, it is not possible for the operator to prevent improper actuation of the knife by engagement of the feeler with portions of the shoe other than the welt end, and, accordingly, there is no opportunity for him to favor the actuation of the welt severing knife as the characteristics of the shoe and the peculiarities of the type of work being performed require. For this reason it has been found desirable to provide the Pickford et al. machine with a safety switch for preventing improper actuation of the welt severing knife and a manually operated latch for rendering the safety switch inoperative. To assist the operator of the prior machine in determining the proper time to render the safety switch inoperative a pointer has been secured in a fixed position on the frame of the prior machine just above the point at which the welt severing knife is located. With such arrangement it is incumbent upon the machine operator to actuate the safety switch releasing latch at a time as close as possible to the approach to the pointer of the visible stitching at the leading end of the seam. However, this can be done only by viewing the upper tread surface of the sole on the shoe and by estimating the distance between the location of the feeler and the point where the first visible stitch on the shoe sole appears.

To avoid the necessity for the use of a safety switch with a latch and the practice of estimating the distance between the feeler and the first visible stitch on the upper surface of an outsole, in accordance with an important feature of the present invention, actuation of the welt-severing knife is no longer controlled by an obscured feeler but is effected by the engagement of a length of thread extending from the first stitch of a seam inserted by the machine with a control switch actuating member. As a prerequisite for such manner of operation the spacing between the first stitch of a new seam and the leading end of the welt is maintained within a fixed distance as will be explained.

In the use of the thread length extending from the first stitch of a new seam to actuate the thread severing knife, the thread length is held taut by the operator at an acute angle to the outsole of the shoe as the first stitch of the seam approaches the operating point a second time after having nearly completed the circuit of the projecting marginal portions of the shoe sole being sewn. This is not an additional duty imposed upon the operator, since it is customary for him to hold this length of thread taut to prevent it from becoming entangled with the needle and others of stitch forming devices when the stitches being formed overlap the first end of the seam.

Referring more particularly to the drawings, the construction and mode of operation of the machine, except as hereinafter described is substantially the same as that in the machines of the prior patents above referred to. A shoe upper having a projecting marginal portion is indicated at 2 (see FIG. 4) and an outsole at 4, both mounted on a last 6 and presented to the sewing point of the machine where the work piece comprising the projecting marginal portions is engaged between a work support 8 (FIG. 1) acting at the under side of the work piece, and a presser foot 10 engaging the upper side of the work piece (see FIG. 4). The work support and presser foot are actuated to grip the work and to move the work in the direction of feed while gripping the work. The stitch

forming devices of the machine include a curved hook needle 12 acting to engage the shoe from the upper side, a work penetrating awl 14, a needle looper 16, a thread finger 18, a loop spreader 19, a shuttle (not shown) and other lock stitch forming and thread handling devices disclosed more fully in the patents above referred to.

The work support 8 is secured to the forward end of a feed carriage 20 mounted for oscillation about a vertical spindle (not shown). Oscillating movement of the carriage 10 and simultaneous clamping and releasing movements of the presser foot cause the welt to be fed along the work support. To direct the welt or similar strip of material along the work support toward the point of operation of the needle, there is secured to a portion 15 of the carriage 20 by means of screws 22 a block 24 forming a welt guide and having an upwardly inclined welt guiding passageway 26. The upper end of the passageway 26 emerges from the block 24 from below the level of the work engaging surface of the work support 20, so that the welt indicated at 27 (FIG. 4) extends upwardly through the passageway and is gripped between the work support and presser foot along with the projecting marginal portions of the shoe. A difficulty common to this type of machine is experienced in obscuring the 25 operator's line of vision to the point of application of the welt to the shoe when the shoe is presented to the machine.

To sever the welt at the end of a seam the welt guide block 24 is provided with a guideway 28 entering the welt 30 guide passageway 26 and forming therewith an angle of about 45°, the guideway extending upwardly at an angle of about 25° to the vertical. Within the guideway 28 is a chisel member sharpened with a cutting edge on its upper end, constituting a welt severing knife 30 spaced in advance of the point of needle operation and movable transversely of the guide. The lower end of the knife 30 is secured within a diametric cut in a plunger 32 slidably mounted in the feed carriage 20, so that upward movement of the plunger 32 will actuate the knife 40 across the welt guide passageway 26 to sever the welt 30 therein with a bevel cut, as a shoe sewing operation is being completed, the knife and plunger being mounted for movement with the feed carriage 20 carrying the work support, so that there is no possibility of displacing the welt 27 from the work engaging surface of the work support during sewing operations.

To actuate the welt severing knife 30 electromagnetic means is provided including the lower end of the plunger 32 having a conical head 34 pressed downwardly by a spring 36 compressed between the carriage 20 and the head 34. The head 34 acts against an upper horizontal face 38 of an enlarged head on the upper end of a stem 40. The stem 40 is slidably mounted in a guideway of a bracket 42 secured to a stationary frame portion of the machine. The arrangement of the conical head 34 and the face 38 on the stem 40 enables the carriage member 20, in which the knife actuating plunger 32 is slidably mounted to move in the direction of feed and to be back fed with the work support and presser foot without changing the vertical position of the knife 30. In severing a welt the knife 30 enters the welt guide passageway 26 and cuts the welt against the upper surface of that passageway.

At the lower end of the stem 40 is a pivotal connection with the upper end of a pair of links 44 having their lower ends similarly connected by a pin 46 (see FIG. 2) to the upper end of a link 48, which is pivoted in turn to a bracket 50 secured to the machine frame, indicated at 52. The pin 46 connecting the links 44 and 48 forms a knee joint for a toggle which is moved toward and from a position of alignment with the pivot points at the upper and lower ends of the links to cause the welt severing knife to be actuated. The pin 46 also passes through one end of a horizontal link 54, the other end of which is pivotally connected to an arma-

ture 56, slidably mounted in a solenoid 58 secured to the frame 52 of the machine. When the solenoid is energized the toggle 44, 48 is straightened and the knife 30 moves across the passageway 26 to sever the welt. When the solenoid 58 is de-energized the toggle is retracted to a position of misalignment between the pivots for the links by a spring 60 (FIG. 2) stretched between the pin 46 and a pin 62 on the frame of the machine. The links 44 have secured to them a handle 64 which may be depressed by the operator to cause the welt to 10 be severed manually rather than automatically.

To actuate the welt severing knife automatically the solenoid 58 is energized through electrical connections with a control switch connected mechanically to the presser foot 10 entirely above the level of the work piece, so that the control switch is clearly visible to the operator and moves with the presser foot as the presser foot engages and disengages the upper surface of the work piece during sewing operations. In this way the relationship of the control switch and the upper surface of the work piece is maintained uniformly constant.

For actuating the control switch with reliability there is mounted on the machine of the present invention, at a position of unobscured visibility, means including a reversely bent thread guiding member 66. The guiding member 66 is mounted above the upper surface of the work piece and is secured by a screw 68 to a lever 70 (FIG. 4) which supports the presser foot 10. The lever 70 corresponds to a lever 385 disclosed in the patent to Gouldbourn et al. above identified.

The control switch has a contact 72 (see FIG. 1) mounted on an insulating sleeve 74 secured in a flange projecting forwardly from the thread guiding member 66. Co-operating with the contact 72 is a contact 76 secured to a downwardly extending flat spring blade 78 attached by a screw 80 to an insulating block 82 mounted on a forwardly projecting flange of the thread guiding member 66, the lower end of the blade 78 extending between arms of the guiding member. For mounting the block 82 the thread guiding member has a counterbored hole through which passes a fastening screw 84 received within a threaded opening in the block. During the normal progress of sewing, an end length, indicated at 86 (FIGS. 3 and 4), of the shuttle or locking thread, is held taut along that portion extending from the last stitch of a seam and engages a lower extension of the blade 78 to bring the contact 76 into engagement with the fixed contact 72 of the control switch.

The arms of thread guiding member 66 are reversely and forwardly bent, overlapping each other in vertically spaced relationship, so that as viewed from above they appear to cross each other (FIG. 3).

The length 86 of the thread end held taut by the operator enters the space between the arms of the thread guiding member as the feeding movement of the shoe continues. The lowermost arm of the thread guiding member is pointed somewhat forwardly at the front of the machine to lift the thread length 86 upwardly away from the surface of the shoe sole and to bring it with certainty into engagement with the blade 78, which extends in close proximity to the upper surface of the work piece. The uppermost arm of the thread guiding member 66 also is pointed forwardly at the front of the machine to guard the blade 78 from premature contact with the thread length 86. Accordingly, less attention and skill is required of the operator than heretofore and greater opportunity, than in the prior machine, is given to him to observe the action along other areas where control of movements is vital to a successful sewing operation.

A shoe ordinarily is presented to the stitch forming devices of an outsole stitching machine in sole uppermost relation to enable the projecting marginal portions of the shoe to be clamped securely between the

5

45

work support 8 and the presser foot 10. In order to insure proper formation of the first stitch in a lock-stitch outsole sewing machine, thread end portions of ample length are withdrawn from the supplies of locking and needle thread before the shoe is presented to the machine. A starting position of the seam ordinarily is selected along the shank of the shoe where the angle formed between the projecting marginal portion and the bulging upper of the shoe is the smallest, thus providing an opportunity for minimizing any minor unsightliness caused by improper starting or failure to butt the ends of the welt accurately. After starting the first stitch of the seam the shoe is guided and positioned at varying angles to insure a reliable stitch forming operation throughout the length of the seam.

In order to reduce the possibility of irregularities, a careful operator grasps and holds the thread end lengths during insertion of the first few stitches. Thereafter, as the shoe is fed the operator releases the thread lengths and continues sewing about the projecting marginal portions of the shoe until he observes the first stitch of the seam again approaching the operating point. At this time most operators grasp the length 86 of the shuttle or locking thread extending from the first stitch of the seam in order to prevent it from being entangled or drawn into the work during insertion of the final stitches, particularly where as in the case of a stitchdown shoe the final stitches are inserted in overlapping relation to the first stitches. In grasping the leading end of shuttle thread, the operator draws it taut against the securement of the first stitch to an acute angle position with relation to the sole of the shoe and at substantially right angles to the adjacent sole edge as viewed from the front of the machine. In so doing he brings the shuttle thread naturally into the space between the arms of the thread guiding member 66, so that no special skill or attention is required. Since the thread guiding arms of the member 66 are carried by the presser foot lever they will always occupy the same heightwise position relatively to the tread surface of the outsole 4, and therefore the end length 86 will always be in a suitable position for it to pass between the thread guiding arms and against the spring blade 78. After engaging the spring blade 78, which terminates just above the level of the lowermost arm on the thread guiding member, the taut length of shuttle thread slips beneath the spring blade and the blade returns to its original position, disengaging the contacts 72 and 76.

Upon closing the contacts 72 and 76 the solenoid 58 is energized by the circuit shown diagrammatically in FIG. 1. Alternating current is supplied by a source of power 88 through a main switch 90 and a transformer 92 from which the current passes through a conductor 94 to the screw 80 and the spring blade 78. When the contact 76 is moved by the locking thread length 86 into engagement with the contact 72, the current passes through a conductor 96 to a coil of a relay 98, which when energized causes a circuit to be completed through the solenoid 58 and back to the source of power 88. After completing the sewing operation upon one shoe, the presser foot 10 is raised to release the shoe.

To enable the first stitch of a seam to be inserted in a predetermined spaced relation from the leading end of the welt first attached to the shoe the operator moves the severed end of the welt remaining in the machine through the welt guide passageway 26 to an indicating mark 100 on the work support before starting the machine in operation on a new shoe. The position of this indicating mark is measured from the point of operation of the knife 30 and is spaced from the knife by an amount equal to the distance between the leaf spring 78 and the point of operation of the needle and awl on the work. Thus, during the first work penetrating stroke of the needle and awl, the first stitch of a seam will be formed and when the first stitch again ap-

proaches the sewing point, the end length of the thread when held taut at right angles to the edge of the projecting marginal portions of the shoe will engage the spring blade 78 at the exact distance from the welt severing knife as will be required to bring the severed trailing end of the welt into abutting relationship with the leading end of the welt first attached to the shoe. In this way it is unnecessary to provide a safety switch which must be rendered inoperative by the operator substantially in advance of the completion of a seam, since the spring blade 78 is well guarded by the thread guiding member 66 against accidental contact or other irregular manner of operation. Also, with a little experience an operator may be able to alter the position of the locking thread end length slightly with respect to the sole edge of a shoe or to modify the operation by increasing or decreasing the tension in the taut thread in compensation of irregularities or other factors peculiar to the type of work operated upon. Thus, the abutting of the welt ends is completed in a uniform desirable manner.

The nature and scope of the invention having been indicated and a particular embodiment having been specifically described, what is claimed is:

1. A machine for attaching a welt to a work piece, said machine having stitch forming and feeding devices, comprising a work support for an under side of the work piece, a presser foot engaging the upper side of the work piece, a needle acting to engage the work piece from the upper side, a guide located below the level of the work piece for directing movement of the welt along the work support toward the point of operation of the needle at a position obscured by the work piece, a welt severing knife spaced in advance of the point of needle operation and movable transversely of the guide, and electromagnetic means for actuating said knife including a control switch connected with said electromagnetic means, in combination with means mounted entirely above the level of the upper surface of the work piece at a position of unobscured visibility for actuating the control switch.

2. A machine for sewing a welt to a work piece with a thread seam, said machine having stitch forming and feeding devices, comprising a work support for the underside of the work piece, a presser foot engaging the upper side of the work piece, a needle acting to engage the work piece from the upper side, a guide for directing the welt along the work support toward the point of operation of the needle at a position obscured by the work piece, a welt severing knife spaced in advance of the point of needle operation and movable transversely of the guide, and electromagnetic means for actuating said knife including a control switch connected with said electromagnetic means, in combination with means for actuating the control switch mounted entirely above the upper surface of the work piece at a position of unobscured visibility where it may be engaged by a length of taut thread extending from the first stitch of the seam, and means on the work support to enable the first stitch of the seam to be inserted in a predetermined spaced relation from the leading end of the welt first attached to the shoe.

3. A machine for attaching a welt to a work piece, said machine having stitch forming and feeding devices for inserting a lock stitch thread seam, a work support for the underside of the work piece, a presser foot engaging the upper side of the work piece, a needle acting to engage the work piece from the upper side, a guide for directing movement of the welt along the work support toward the point of operation of the needle at a position obscured by the work piece, a welt severing knife spaced in advance of the point of needle operation and movable transversely of the guide, and electromagnetic means for actuating said knife including a control switch connected with said electromagnetic means, in

combination with a spring blade extending from the control switch into close proximity with the upper surface of the work where a length of taut thread extending from the first stitch of the seam will engage the blade at a position clearly visible to the operator.

4. A machine for attaching a welt to a work piece, said machine having stitch forming and feeding devices for inserting a lock stitch thread seam, a work support for the underside of the work piece, a presser foot engaging the upper side of the work piece, a needle acting to engage the work piece from the upper side, a guide for directing movement of the welt along the work support toward the point of operation of the needle at a position obscured by the work piece, a welt severing knife spaced in advance of the point of needle operation and movable transversely of the guide, and electromagnetic means for actuating said knife including a control switch connected with said electromagnetic means, in combination with a spring blade extending from the control switch into close proximity with the upper surface of the work where a length of taut thread extending from the first stitch of the seam will engage the blade at a position clearly visible to the operator, and a thread guiding member acting to direct the taut thread length into engagement with the blade extending from the control switch.

5. A machine for attaching a welt to a work piece, said machine having stitch forming and feeding devices for inserting a lock stitch thread seam, a work support for the underside of the work piece, a presser foot engaging the upper side of the work piece, a needle acting to engage the work piece from the upper side, a guide for directing movement of the welt along the work support toward the point of operation of the needle at a position obscured by the work piece, a welt severing knife spaced in advance of the point of needle operation and movable transversely of the guide, and electromagnetic means for actuating said knife including a control switch connected with said electromagnetic means, in combination with a spring blade extending from the control switch into close proximity with the upper surface of the work where a length of taut thread extending from the first stitch of the seam will engage the blade at a position clearly visible to the operator, and a thread guiding member having reversely bent arms overlapping each other in vertically spaced relationship between which the taut thread length is directed into engagement with the blade extending from the control switch.

6. A machine for attaching a welt to a work piece, said machine having stitch forming and feeding devices for inserting a lock stitch thread seam, a work support for the underside of the work piece, a presser foot engaging the upper side of the work piece, a needle acting to engage the work piece from the upper side, a guide for directing movement of the welt along the work support toward the point of operation of the needle at a position obscured by the work piece, a welt severing knife spaced in advance of the point of needle operation and movable transversely of the guide, and electromagnetic means for actuating said knife including a control switch connected with said electromagnetic means, in combination with means for actuating the control switch including a thread guiding member having reversely bent arms overlapping each other in vertically spaced relationship between which the taut thread length is directed and a spring blade extending from the control switch entering between the reversely bent arms of the thread guiding member to cause the taut thread to engage the blade.

7. A machine for attaching a welt to a work piece, said machine having stitch forming and feeding devices for inserting a lock stitch thread seam, a work support for the underside of the work piece, a presser foot engaging the upper side of the work piece, a needle acting to engage the work piece from the upper side, a guide for directing movement of the welt along the work support toward the point of operation of the needle at a po-

sition obscured by the work piece, a welt severing knife spaced in advance of the point of needle operation and movable transversely of the guide, and electromagnetic means for actuating said knife including a control switch connected with said electromagnetic means, in combination with means for actuating the control switch including a thread guiding member having reversely bent arms overlapping each other in vertically spaced relationship between which the taut thread length is directed, and a spring blade extending downwardly from the control switch with its lower end terminating above the level of the lowermost arm on the thread guiding member.

8. A machine for sewing a welt to a work piece with a thread seam, said machine having stitch forming and feeding devices, comprising a work support for the underside of the work piece, a presser foot engaging the upper side of the work piece, a needle acting to engage the work piece from the upper side, a guide for directing the welt along the work support toward the point of operation of the needle at a position obscured by the work piece, a welt severing knife spaced in advance of the point of needle operation and movable transversely of the guide and electromagnetic means for actuating said knife including a control switch connected with said electromagnetic means, in combination with means for actuating the control switch mounted entirely above the upper surface of the work piece at a position of unobscured visibility where it may be engaged by a length of taut thread extending from the first stitch of the seam, including a thread guiding member having reversely bent arms crossing each other as viewed from above with the lowermost arm pointed somewhat forwardly to lift the taut thread length upwardly away from the surface of the work piece and a spring blade extending from the control switch and entering between the reversely bent arms of the thread guiding member to bring the taut thread with certainty into engagement with the spring blade.

5 9. A machine for sewing a welt to a work piece with a thread seam, said machine having stitch forming and feeding devices, comprising a work support for the underside of the work piece, a presser foot engaging the upper side of the work piece, a needle acting to engage the work piece from the upper side, a guide for directing the welt along the work support toward the point of operation of the needle at a position obscured by the work piece, a welt severing knife spaced in advance of the point of needle operation and movable transversely of the guide and electromagnetic means for actuating said knife including a control switch connected with said electromagnetic means, in combination with means for actuating the control switch mounted entirely above the upper surface of the work piece at a position of unobscured visibility where it may be engaged by a length of taut thread extending from the first stitch of the seam, including a thread guiding member having reversely bent arms crossing each other as viewed from above with the lowermost arm pointed somewhat forwardly to lift the taut thread length upwardly away from the surface of the work piece and a spring blade extending from the control switch and entering between the reversely bent arms of the thread guiding member to bring the taut thread with certainty into engagement with the spring blade, the uppermost arm of the thread guiding member being pointed forwardly to guard the spring blade from premature contact with the taut thread length.
